DRAFT OPERATED COMBUSTION AIR INLET
CONTROL DEVICE FOR COMBUSTION APPARATUS

Perry S. Martin, Harrisonburg, Va.

Application November 3, 1947, Serial No. 783,816

3 Claims. (Cl. 126—290)

1

My invention relates to a thermostatically actuated, automatically operating temperature control device of the type especially adapted for use in regulating the supply of combustion air delivered to a solid fuel burning apparatus.

One object of the invention is to produce an improved temperature control device of the type set forth.

Temperature control devices usually function by moving a damper from fully closed to partly, or fully, open position. In order to obtain a fairly accurate control, the damper should be as light and as free of friction as possible.

It is therefore a further object of the invention to produce an improved temperature control device in which the arrangement, mounting and location of the damper or dampers, are such that the amount of friction present is negligible and in which the dampers are relatively light.

A still further object is to produce an improved temperature control device which employs a pair of dampers which are so located relative to each other and to the direction of flow of air through the openings controlled by the dampers, so that the dampers are in almost, but not quite, balanced condition whereby minimum power will have to be exerted by the thermostat to move the dampers.

A still further object is to produce an improved temperature control device in which the imbalance of the dampers is utilized to cause the dampers to tend to close, in windy weather.

A still further object of the invention is to produce a simple, inexpensive and durable temperature control device of the character set forth.

These and other objects are attained by my invention as set forth in the following specification and as shown in the accompanying drawings in which:

Fig. 1 is a top plan view of a temperature control device embodying my invention, the same being shown attached to a portion of the wall of a solid fuel burning stove.

Fig. 2 is a vertical section on line II—II on Fig. 1 with the wall of the stove omitted, and with the dampers shown closed.

Fig. 3 is a horizontal section on line III—III on Fig. 2.

Fig. 4 is similar to Fig. 2 but with the dampers shown open.

Fig. 5 is a view similar to Fig. 2, illustrating another embodiment of the invention.

Fig. 6 is a fragmentary elevational view looking in the direction of line VI—VI on Figs. 2 and 5.

2

Fig. 7 is a fragmentary, sectional view taken on line VII—VII on Fig. 5.

Fig. 8 is a fragmentary sectional view taken on line VIII—VIII on Figs. 2 and 5.

Fig. 9 is a perspective view of the damper assembly, looking in the direction of line IX—IX on Figs. 2 and 5.

In both embodiments of the invention the temperature control device includes a draft tube connectable to the combustion chamber of a solid fuel burning stove and thermostatically operated dampers for controlling the flow of combustion air through said tube. The draft tube, the dampers and the casing of the control device are preferably made of inexpensive and easily fabricated sheet metal.

The draft tube may have any desired cross sectional shape but, as shown, it is square or rectangular, and it is formed of side walls 10, 20 a bottom wall 11, a top wall 12 and one end wall 13. The other end of the draft tube is unobstructed and is attachable, in any well known manner, to the air inlet of the combustion chamber of a solid fuel burning stove only a portion 25 of which is shown in Fig. 1.

The draft tube is provided with an air inlet opening 16 formed in the top wall 12 and with an air inlet opening 18 in the end wall 13 thereof. It will be noted that the opening 16 is in a horizontal plane while the opening 18 is in a vertical plane and that the opening 16 is smaller than the opening 18. It will also be noted that the damper 20 which closes the opening 16 has a smaller area than the damper 21 which closes the opening 18 and that the damper 20 moves to closing position against the direction of the flow of air through the opening 16, while the damper 18 moves to closing position with, or in the direction of the flow of the air through the opening 18. These are all important features of the invention and will hereinafter be more fully described.

The dampers 20 and 21 are carried by the horizontal and vertical arms 23 and 24, respectively, of a right-angle bracket, which is best shown in Fig. 9. The arm 23 is provided with a slot 25 (Fig. 9) through which extends a tongue 26 formed on the upper edge of a vertically disposed wall 27 of a U-shaped bracket the bight portion 28 of which is suitably secured to the top wall 12 of the draft tube. The upper edge of the wall 27, on either side of the tongue 26, in cooperation with the tongue 26 and the slot 25 form a knife edge pivot bearing for the damper supporting bracket. In other words the arm 23 of the damper bracket is mounted, and

functions, like a balance beam as is clearly shown in Fig. 9.

The dampers are so arranged that, when entirely free to move, that is, when they are not acted on by air or by the thermostat, they will assume the non-obstructing position of Fig. 4 in which the damper 20 drops below the opening 16 and the damper 21 moves away from the opening 18. This is effected by weighting the damper 20 or by making the arm 23 longer than the arm 24, or by both of these expedients.

The movement of the dampers to the open position is limited by contact of the underside of the arm 23 with the upper edge of the other limb 29 of the U-shaped bracket, as shown in Fig. 4. The damper 20 is secured to the free end of the arm 23 by a chain or a link 30 and the damper 21 is secured to the lower end of the arm 24 as shown at 32 in Figs. 2 and 5, or in any other suitable manner.

The dampers are moved from the open position of Fig. 4 to the closed position of Fig. 2, or to any position in between, by pressure applied to the arm 24 by the lower portion 34 of a lever 35, the upper portion 36 of which is secured at 37 to the vertical portion 38 of an angle member the horizontal portion 39 of which is pivoted at 40 in a slot formed in a vertical wall 42 of the casing of the thermostat.

The lever 35 is actuated by a heat responsive element such as a wafer thermostat 46 which is mounted adjacent the upper portion 36 of the lever. When the thermostat expands, the knob 47 thereof moves to the left, as shown in the drawings, and bears upon the arm 38 and the upper portion 36 of the lever 35 with a pressure which varies with the heat to which the thermostat is subjected. When the heat reaches a predetermined value, the pressure exerted will begin to move the arm 35 to the left and will cause it to exert pressure on the arm 24 in a direction partly or wholly to close the damper 21 and, hence, the damper 20. The thermostat 46 is carried by an arm 50 which is pivotally suspended, at 51, from a wall 52 forming part of the casing. By this means the thermostat can be moved towards or away from the upper portion of the arm 35 to predetermine the extent to which the thermostat must expand before it will actuate the dampers.

The thermostat is adjusted, or moved to the desired position relative to the arm 35 by a cam 54 which is rotatable by a knob 55 journalled in a wall of the casing. By turning the knob, the cam 54 will be turned to cause a relatively high, or a relatively low, portion thereof to bear against the portion 59 of the arm 50 to move the thermostat 46 further to the left as shown in the drawings. The arm 50 is so constructed that, in the absence of pressure by the cam 54, the thermostat will be in the position of Fig. 4 in which it exerts no pressure on the lever 35 and the dampers are left free to move, by gravity, their non-obstructing position.

The operation is as follows:

As the room temperature rises, the thermostat 46 expands and exerts pressure on the upper portion 36 of the lever 35. The lever 35 being rigid, and being pivoted at 40, the pressure exerted by the thermostat on its upper portion will move the lower portion 34 thereof, and, hence, the damper 21, in a direction to close the opening 18. Movement of the damper 21 horizontally toward the opening 18 causes the damper 20 to move upwardly toward the opening 16, and vice versa.

Whether the dampers close the inlet openings fully, or whether they only partly restrict the flow of air by reducing the clearance between the dampers and the walls 12 and 13 depends on the degree of heat to which the thermostat is subjected.

Conversely, when the thermostat is fully contracted, which happens when the temperature to be controlled falls to a predetermined value, the knob 47 ceases to press against the upper end of the lever 35 and the dampers automatically revert to the open position of Fig. 4.

It will be noted that, in opening, the damper 20 moves downwardly, or in the direction of the flow of air through the opening 16 and that, in opening, the damper 21 moves in a direction opposed to the direction of the flow of air through the opening 18. However, and as above pointed out, the area of the damper 21 is greater than the area of the damper 20 so that the damper 20 must be so weighted as to overcome the excess air pressure which is exerted on the damper 21. Further, because the movement of the damper 21, in opening direction, is against the static pressure of the air, as well as against the dynamic pressure of the air flowing in the direction of the opening 18 in response to reduced pressure within the stove, the movement of both dampers will be gradual, rather than abrupt and, therefore, the operation of the dampers will be free of clanking and other noises which may be caused by sudden movement or impact of metallic parts. The same is of course true when the dampers move to closing direction because, then, the damper 20 will be moving against the pressure of the air flowing through the opening 16.

The arrangement of the dampers, whereby they are almost, but not quite in balance, leaves very little work for the thermostat. In other words, a very slight expansion of the thermostat will be enough to overcome the slight imbalance and the insignificant friction and inertia present and will move the dampers accordingly. Therefore, a sensitive thermostat can be used and a very accurate control of the temperature to be regulated can be had.

In blustery weather, the air tends to flow through the openings 16 and 18 at a more rapid rate. This increases the combustion and increases the negative pressure within the stove thus further accelerating the flow of air through the inlet openings. If this condition is allowed to prevail until the room air is warm enough to cause the thermostat to close the dampers, there will be a more or less serious temperature over-ride. Therefore, to prevent or minimize such temperature over-ride, it is necessary to close the dampers somewhat before the room temperature has reached the desired maximum value.

This problem is also solved by making the damper 21 of slightly larger area than the damper 20 so that the excess air pressure exerted on the outer surface of the damper 21, as compared with the pressure exerted on the upper side of the damper 20, will tend to move the dampers toward closing position thus automatically reducing or shutting off the supply of air. Also, while this is taking, or is about to take, place, the thermostat will have begun to expand and while the expansion may not have, as yet, become enough, of its self, to move the dampers to partly or wholly closed position, it will be found that, the action of the thermostat, assisted by the pressure differential on the dampers, will cause the dampers to close partly, or wholly, thus reducing or

shutting off the air supply before the room temperature has reached the desired value. The heat already generated, and the heat which will continue to be generated by the increased combustion, induced by the increased supply of air prior to the closing of the dampers, will be enough to bring the room temperature up to the desired value with little or no over-ride.

By turning the cam 54 so as to move the thermostat nearer to the lever 35, the amount of expansion of the thermostat needed to move the dampers to closing position will be reduced and a relatively low room temperature will be maintained, and vice versa.

While I have described the invention as applied to a solid fuel heating stove, it is of course evident that my novel arrangement of dampers can be used to control the passage of air to, or through, other heat producing apparatus.

In order to prevent, or minimize, over-ride or the opposite effect, in the temperature to be controlled, during ordinary weather and wind conditions, I enclose the thermostat in an improved casing so arranged that the thermostat is alternately bathed in streams of air of different temperatures, depending on whether the dampers are closed or open so that the thermostat will have anticipatory action and will move the dampers in one direction or the other somewhat before it would have otherwise done so.

As shown, the thermostat is positioned in a compartment 60 defined by the wall 42, front wall 61, side walls 62, and the top wall 63^x. The front wall 61, and side walls 62 extend downwardly to the draft tube to form an extension of the compartment 60. The lower end of the compartment 60 is open and the side walls 62 of this compartment are provided with apertures 63. The top wall 63^x of the compartment is provided with one or more openings 64 and the wall 42 is provided with upper and lower openings 65 which lead to an intermediate compartment 66 formed between the wall 42 and a wall 68. The wall 68 cooperates with a bottom wall 70, a vertical wall 72 and the side walls 62 to form a second compartment 74 which is provided with one or more top openings 76 and which communicates through an opening 78 with the compartments 66 and 60. When the control device is in position, the wall 72 and the compartment 74 are immediately adjacent the wall 14 of the stove and are subjected to the high temperature prevailing in the vicinity of the stove. The compartment 60 in which the thermostat is located is separated from the compartment 74 by the intermediate dead air space or compartment 66. Therefore, the thermostat is effectively insulated from the heat of the stove. On the contrary, the thermostat, except as hereinafter explained, is constantly bathed by the air of the room the temperature of which is to be controlled, the room air being free to circulate through the compartment 60.

However, when the dampers are open, the air flowing through the openings 16 and 18 tends to entrain air from the lower portion of the compartment 60 and produces reduced pressure in the compartment 60. This causes room air to flow through the top openings 64, 65, 76 and 78, downwardly over the thermostat. Since the air flowing through the openings 76 and 78 comes from the vicinity of the stove and is hotter than the room air entering through the opening 64, the thermostat will be subjected to air having a mean temperature higher than the temperature of the air in the rest of the room. The thermo-

stat will thus begin to close the dampers a little before the room air temperature has reached the desired value. By this means, the heat which will continue to be generated, even after the air supply is reduced or cut off, will bring the room temperature to the desired value. This prevents the rise of the temperature to be controlled much above the desired value.

Conversely, when the dampers are closed, room air will flow through the open, lower end of the compartment 60 and through the openings 63, upwardly through the compartment 60 and out through the top openings. By this means the thermostat is subjected to the temperature of the room, exclusively, and will therefore permit the dampers to open as soon as the room temperature falls to a given value. The room air thus bathing the thermostat shields it from any direct heat from the stove which would otherwise expand the thermostat and thus delay the opening of the dampers and will thus permit the room temperature to fall below said given minimum value.

In Fig. 5 I have shown another embodiment of the invention in which I include a second thermostat the function of which is to close the dampers in response to excessive heat which might result from a failure of the thermostat 46 to operate as intended.

The secondary or safety thermostat illustrated is formed of a bimetallic element 80, disposed in the compartment 74, and carried by a bracket 82 secured to the wall 72. The element 80 is connected by means of an adjustment screw 84 to a lever 88 which is pivoted at 40 to the wall 68 and which is secured at 37 to the upper portion 36 of the damper actuating lever 35. As the bimetallic element is heated, the upper arm thereof moves in counterclock-wise direction thus pivoting the lever 88 and causing the pendant portion thereof to press against the upper portion of the lever 35 to move the dampers to closing direction, and vice versa.

By turning the screw so as to cause it to move downwardly relative to the lever 88, the play between the element 80 and the head of the screw is reduced. Therefore, a relatively small expansion of the bimetallic element will move the dampers in closing direction and, vice versa.

What I claim is:

- 50 1. A temperature control device including a casing adapted to have one end thereof connected, in air-flow relation, to the air intake of a combustion chamber, there being a first air inlet opening in a first wall of said casing and a second air inlet opening in a second wall of said casing, said second opening being spaced from said first opening and said walls being in planes which intersect to form an angle which is less than 180 degrees, a first damper for closing said first opening, a second damper for closing said second opening, an angle member having a first arm and a second arm, means connecting the end of said first arm to said first damper, means connecting the end of said second arm to said second damper, and supporting means pivotally supporting said angle member at point adjacent the junctions of said arms, whereby arcuate movement of said arms about said last mentioned means will bodily move said dampers jointly toward, and away from, their respective openings, said angle member and said supporting means being located wholly outside of said casing.
- 65 2. The structure recited in claim 1 in which the dampers and the arms of the angle member are so arranged and weighted that, in the absence
- 70 75

of other influences, said first damper will move, by gravity, to a non-obstructing position with reference to said first opening and will move the second damper to a non-obstructing position with reference to the second opening.

3. The structure recited in claim 1 in which the first damper moves toward the non-obstructing position in the direction of the flow of air through said first opening and the second damper moves toward the non-obstructing position against the direction of the flow of air through the second opening, and in which the surface area of the first damper is less than the surface area of the second damper, the weight differential being substantially balanced by the greater air resistance of the second damper.
